(57) **CLAIM**

The ornamental design for a speaker timing device, as shown and described.

DESCRIPTION

FIG. 1 is a perspective view of my new speaker timing device taken from the right front;

FIG. 2 is a front view of my new design;

FIG. 3 is a rear view of my new design;

FIG. 4 is a left side view of my new design; and,

FIG. 5 is a right side view of my new design.

The broken line illustration of environmental structure in the drawing is not part of the design sought to be patented.
